UNITED STATES PATENT OFFICE.

WILLIAM W. HARRIS, OF PONTIAC, MICHIGAN.

PRIMING-CUP.

1,339,884.

Specification of Letters Patent. Patented May 11, 1920.

Original application filed January 12, 1918, Serial No. 211,652. Divided and this application filed October 25, 1918, Serial No. 259,610. Renewed August 30, 1919. Serial No. 320,821.

To all whom it may concern:

Be it known that I, WILLIAM W. HARRIS, a citizen of the United States of America, residing at Pontiac, county of Oakland, 5 State of Michigan, have invented certain new and useful Improvements in Priming-Cups, of which the following is a specification.

This invention relates to priming cups.

10 More particularly, the invention relates to priming cups for gas and other explosive engines comprising a body shell having a fluid receiving chamber constructed at its top to provide a fluid receiving opening and 15 constructed at its bottom to provide a co-operating discharge opening, and a self-centering valve for effecting closure of the fluid discharge opening and loosely retained within the cup for compensating for lateral 20 movement of the valve relatively to the body shell.

This application is a divisional application 25 of my copending application Serial No. 211,652, filed by me on the 12th day of January, 1918, and entitled Priming cup.

Further features and objects of the present invention will be more fully understood from the following description and the accompanying drawings, in which—

30 Figure 1 is a side elevation of a priming cup embodying my invention;

Fig. 2 is a vertical central sectional elevation of Fig. 1;

Fig. 3 is a vertical sectional central elevation; and

Fig. 4 is a detail top plan view of an element of the construction shown in Fig. 3.

Referring to the embodiment shown in Figs. 1 and 2, the body shell 1 is constructed 40 interiorly to provide for the fluid receiving chamber 2 constructed at its top to receive gasolene or other priming fluid. The body shell 1 is provided at its lower end with the fluid discharging passage 4, preferably having 45 a valve seat. The receiving chamber 2, as shown, may be of an inner shell 7 suitably retained at its upper edge within the body shell 1 as by crimping or the like. Ex- 50 teriorly, the body shell 1 is of the usual construction and may be provided with the threading 16, for threaded insertion within the shell of the cylinder of the explosive engine.

As shown, the valve 5 may be provided with the valve closure 22 adapted upon be-

ing moved upwardly to close the discharge 55 opening 4 in sealing relation.

Means are provided for loosely mounting the valve stem 5 within the body shell 1 and in the particular embodiment shown in Figs. 1 and 2, such loosely mounting means comprises the internally threaded member 10 threadedly connected with the external thread 13 on the valve stem 5, said member 10 being loosely retained within the inner shell 7 by means of suitable projections 11 60 respectively extending within suitable openings 12 in the inner shell 7. The valve stem 5 projects through the opening 14 upwardly of the body shell 1 and may be provided with suitable means for manipulating the valve 65 stem 5, as by bending the valve stem 5 as indicated at 17. The opening 14 is relatively large as compared with the cross sectional area of the valve stem 5, to thereby permit passage of the gasolene or other priming 70 fluid from the chamber 2 into the discharge passage of the priming cup.

Upon turning the valve stem 5 by means of the manipulating portion 17 to open the discharge opening 4, the valve 22 is moved 80 downwardly and the member 10 is retained loosely relatively to the inner shell 7. Upon turning the valve stem 5 to close the valve 22 against the valve seat 4, the member 10 by reason of its compensating lateral movement 85 effects the self-centering of the valve in its final closing position.

Referring now to the modification shown in Figs. 3 and 4, the means for loosely mounting the valve stem 5 within the body 90 shell 1 comprises the saddle 23 provided with the more or less central opening 25 internally threaded and adapted to be threadedly connected with the external threading 13 of the valve stem 5. The saddle 23 is 95 further provided with the suspending lugs 24 respectively loosely projecting through suitable openings in the body shell, as shown. Otherwise the modification shown in Figs. 3 and 4 corresponds similarly to 100 the modification shown in Figs. 1 and 2, and like parts have been designated by like reference numbers.

By reason of the aforesaid loosely mounting means of the valve stem relative to the 105 casing of the priming cup, as will be apparent upon slightly opening the valve when testing the cylinders of the engine by

operating the engine in the usual manner, my invention serves as an indicator, whether or not the spark plugs of the respective cylinders of the engine are in operating condition, namely, in each of the cylinders in which the spark plug is in sparking order, the valve stem of its priming cup will be vibrated, whereas the cylinder whose spark plug is not in good sparking order, the 10 valve stem of its priming cup will be quiescent.

- It will be noted that the aforesaid embodiments of my invention are readily manufactured by means of simple stamping machines or a simple lathe, and eliminates the 15 relatively high expense and the matter of skilled labor required in providing the usual internally threaded, fixed valve closure for the priming cup.
- 20 The self-centering characteristics of my invention obviates the necessity of absolute perfect fit in construction and in assembling and further affords self adjustment upon wear of the movable parts or in the event 25 of bending or otherwise misshaping any part incident to use.

Whereas I have described by invention by reference to specific forms thereof, it will be understood that many changes and modifications 30 may be made without departing from the spirit of the invention as defined by the appended claims.

I claim:

1. A priming cup for gas engines comprising a body shell having a fluid receiving chamber and a valve-seating opening with a passage therebetween, said shell further having one or more openings, an internally threaded member, one or more 35 lugs on said member and extending into said one or more openings for retaining said member within said shell, an externally threaded spindle in substantially accurately threaded relation with said internally threaded member, said spindle projecting through said valve-seating opening, means disposed on said spindle forming a valve closure for said valve-seating opening and means for mounting said internally threaded 40 member and said externally threaded spindle to provide lateral movement relative to said body shell to an extent sufficient to effect perfect alignment of said valve closure means with said valve-seating opening when said spindle is moved to closing position.

2. In a priming cup for gas engines, the combination of a cup shell constructed interiorly to provide an inner fluid receiving chamber, said cup shell being constructed at its top to provide a fluid receiving inlet, said cup shell being further constructed at its bottom to provide a co-operating fluid discharge opening, a self-centering valve 60 constructed to be moved upwardly to effect

a closure of said fluid discharge opening, and valve actuating mechanism comprising two substantially accurately co-threaded members, means for actuating one of said threaded members and means for loosely retaining the other of said threaded members within said cup, said retaining means being provided with an opening for the passage of fluid therethrough, said retaining means being constructed to provide for 70 compensating lateral movement of the said two co-threaded members relative to said cup shell.

3. A priming cup for gas engines, comprising a body shell having a fluid receiving 80 chamber and a valve-seating opening with a passage therebetween, a secondary inner shell, means for securing said inner shell to said body shell, an internally threaded member loosely mounted within said secondary shell, an externally threaded spindle in substantially accurately threaded relation with said internally threaded member, said spindle projecting through said valve-seating opening, means disposed on 85 said spindle forming a valve closure when said spindle is moved upwardly into engagement with the lower side of said valve-seating opening, said internally threaded member and said externally threaded spindle having a lateral movement relative to said body shell to an extent sufficient to effect perfect alignment of said valve closure means with said valve-seating opening.

4. A priming cup comprising a body shell 100 constructed interiorly to provide an inner fluid receiving chamber and at its top to provide a fluid receiving opening and further provided with a fluid passage, a closure co-operating with said passage, a spindle 105 controlling said closure and means for loosely mounting said spindle within said body shell, said body shell being further provided with one or more openings, said mounting means comprising an element in 110 substantially accurately threaded relation with said spindle and extending into said one or more openings.

5. A priming cup comprising a body shell constructed interiorly to provide an inner 115 fluid receiving chamber and at its top to provide a fluid receiving opening and further provided with a fluid passage, a closure co-operating with said passage, a spindle controlling said closure to close said 120 passage upon upward movement of said spindle, and means for loosely mounting said spindle within said body shell, said body shell being further provided with one or more openings, said mounting means comprising an element in 125 substantially accurately threaded relation with said spindle and extending into said one or more openings.

6. A priming cup comprising a cup shell 130

constructed interiorly to provide a fluid receiving chamber and at its top to provide a fluid receiving inlet, said cup shell being further constructed at its bottom to provide 5 a fluid discharge passage, a self-centering valve constructed to be moved upwardly to effect closure of said fluid discharge passage and valve actuating mechanism comprising two substantially accurately co-threaded members, said cup shell being provided with one or more openings, one of 10 said threaded members extending into said one or more openings.

7. A priming cup comprising a cup shell 15 constructed interiorly to provide a fluid re-

ceiving chamber and at its top to provide a fluid receiving inlet, said cup shell being further constructed at its bottom to provide a fluid discharge passage, a self-centering valve coöperating with said fluid discharge 20 passage and valve actuating mechanism comprising two substantially accurately co-threaded members, said cup shell being provided with one or more openings, one of 25 said threaded members extending into said one or more openings.

In testimony whereof I have signed this specification this twenty-second day of October, 1918.

WILLIAM W. HARRIS.
